APPARATUS FOR CONDITIONING SAND AND
LIKE MATERIALSBenjamin A. Smith, Lakewood, Ohio, assignor to
The C. O. Bartlett & Snow Company, Cleveland,
Ohio, a corporation of Ohio

Application August 14, 1937, Serial No. 159,141

1 Claim. (Cl. 22—89)

This invention relates as indicated to an improved apparatus for treating and reconditioning materials such as foundry sand and the like.

After foundry sand is shaken out of the molds at the conclusion of the casting operation, the same must be cooled, aerated, mixed and generally reconditioned before it can be re-used.

It is the principal object of my invention to provide an apparatus for attaining the above mentioned desirable ends by an improved apparatus characterized in that the process may be carried on continuously, the reconditioning operation carried forth in a relatively small floor area and by virtue of the new principles of my apparatus at a reduced cost as compared with prior art processes.

Other objects of my invention will appear as the description proceeds.

To the accomplishment of the foregoing and related ends, said invention, then, consists of the means hereinafter fully described and particularly pointed out in the claim; the annexed drawing and the following description setting forth in detail certain means and one mode illustrating, however, but one of the various ways in which the principle of the invention may be used.

In said annexed drawing:

Fig. 1 is a side elevational view of an apparatus constructed in accordance with the principles of my invention and capable of carrying out the process of my invention; Fig. 2 is a transverse sectional view of a portion of the apparatus illustrated in Fig. 1 taken on a plane substantially indicated by the line 2—2; Fig. 3 is a transverse sectional view of the apparatus illustrated in Fig. 1 taken on a plane substantially indicated by the line 3—3; and Fig. 4 is a longitudinal sectional view through the rotating shell portion of the apparatus illustrated in Fig. 1.

Broadly stated, my invention comprises the process for reconditioning foundry sand and the like characterized by the fact that the sand to be reconditioned is carried in a continuous stream through a treating chamber such as a horizontally inclined rotatable cylindrical shell in which the sand is thoroughly mixed and aerated by being subjected to the flow of a stream of air axially through said rotatable chamber and more particularly by the fact that the sand, substantially immediately after its introduction into the treating chamber, is sprayed with water, the quantity of which is automatically regulated by the temperature of the treating air stream as it leaves the treating chamber. My invention, furthermore, contemplates the provision of im-

proved apparatus for the purpose of performing the above described process.

Referring now more specifically to the drawing and more especially to Fig. 1, the apparatus here-in illustrated as one modification of the apparatus comprising my invention consists of a horizontally inclined cylindrical shell 1 which, at axially spaced points, is on its outer periphery provided with supporting rings 2 and 3 which rest on paired supporting rollers 4 and 5 respectively, said rollers being rotatably supported by suitable supporting bases 6 and 7. Likewise mounted on the outer periphery of the shell 1 is an annular spur gear 8 which is immersed with a driving pinion 9, the latter being driven through a suitable gear reduction unit 10 by means of a prime mover such as electric motor 11.

Positioned adjacent the upper or charging end of the shell 1 is a loading platform generally indicated at 12. This loading platform supports a charging chute 13 across the mouth of which there may be positioned a screen 14 onto which the mold flasks are shaken out.

Positioned around the opposite end of the shell 1 is a stationary housing 15, which, by means of the backing ring 16 substantially closes this end of the shell against infiltration of outside air. The collecting ring 15 is provided with a discharge chute 17 from which the treated sand is discharged either into a suitable container or a cart to be conveyed back to the molding station.

During normal operation of the apparatus comprising my invention, it will be found desirable to maintain a sufficient quantity of the treated sand in the discharge chute 17 at all times so as to prevent infiltration of cold air at this point into the treating chamber.

Connected with the header or collecting ring 15 is an air conduit 18 which has associated therewith a fan or blower 19 adapted to be driven, for example, by a motor 20. A damper 21 may be provided for the purpose of controlling the rate of air flow through the conduit 18, if and when desired.

Projecting into the open forward or upper end of the shell 1 is a water pipe 22, the inner end of which, as most clearly illustrated in Fig. 4, is provided with a plurality of longitudinally spaced spray nozzles 23. The spray nozzles 23 will be so constructed and arranged that they are capable of delivering a spray of treating water to the hot untreated sand in the feeding or charging end of the shell 1. The water supply pipe 22 will be conveniently provided with a pressure reducing valve generally indicated at 23'. Pressure

reducing valves of this character are so well known to those familiar with the art that a detailed description of its construction and operation is believed unnecessary. Suffice it to say that the valve 23' is employed for the purpose of adjustably controlling the pressure in the water pipe 22 to the left of such valve irrespective of the pressure in the water supply pipe.

The water pipe 22 is further provided with a control valve 24 for the purpose of controlling the rate of flow of water through the pipe 22. The control valve illustrated is a conventional type available in the trade and being concurrently marketed by the Foxboro Instrument Co. This valve 24 is adapted to be actuated and controlled by fluids such as air under pressure led thereto by conduit 25. The air for the conduit 25 may be supplied from any suitable source through the conduit 26 and its rate of flow and consequently the pressure in the conduit 25 is controlled by a regulator 27, likewise of conventional construction and generally available on the open market for purposes of this character. The regulator 27, which is merely diagrammatically illustrated, is likewise available to the trade generally by the Foxboro Instrument Co., so that the description of my invention need not be burdened by a detailed description of the construction and operation of such regulator.

Mounted in the conduit 18 so as to be responsive to fluctuations in the temperature of the discharged air stream is a thermosensitive element 28. This element 28 is connected to the regulator 27 by suitable lead 29 so that as the temperature of the discharged air stream varies, the regulator 27 will correspondingly vary the pressure in the conduit 25 and accordingly, the rate of flow of water through the valve 24 into the line 22.

The interior of the cylindrical treater chamber 1 is more clearly illustrated in Figs. 2, 3 and 4 and from an inspection of these last-named figures, it will be observed that in the feeding end of the cylindrical shell 1 there are provided helically arranged conveyor flights 30 which carry the material into the spraying zone generally indicated at 31. The spraying zone 31 will preferably be provided with a plurality of circumferentially spaced radially inwardly extending flights 32, the form and arrangement of which will be most clearly apparent from an inspection of Fig. 3.

As the shell 1 rotates, the flights 32 mix the material as it is being sprayed by the nozzles 23. The horizontal inclination of the axis of the cylindrical member 1 causes the sand to move forwardly and downwardly therein as the same is being rotated. The flights, throughout the remaining axial extent of the cylindrical member 1, will preferably be arranged in banks generally indicated at 33, 34 and 35. These differ from each other primarily in their deflection from the true radial direction to which the flights 32 extend.

Inasmuch as the material will become increasingly drier as it passes axially through the treating cylinder 1, the angle of repose of such material will become progressively less. Accordingly, the banks of flights 33, 34 and 35 will be progressively inclined to a greater degree so that as the material passes through the treater shell, a substantial portion thereof will be at all times showered downwardly by the lift flights across the cross-sectional area defined by the cylindrical chamber 1.

In the operation of the above described appa-

ratus comprising one form of my invention and in carrying out the improved process of my invention, it will be observed that the hot sand just previously discharged from the molding flasks is first sprayed with water. The actual heat transfer between the hot sand and the cold water will result in a partial cooling of the sand. The amount of water introduced, however, will not be sufficient to completely cool the sand down to the desired temperature. This remaining reduction in temperature is effected as a result of actual heat transfer between the stream of treating air drawn through the treating chamber by the blower 19 and by an evaporation from the sand of the water initially sprayed thereon.

In order to insure that a proper balance will be maintained at all times between the flow of sand, its temperature, the rate of flow of air, its temperature, and the amount of water introduced to the sand, so that the finally treated sand discharged from the apparatus will have the proper moisture content and be of the proper temperature, the thermostatic regulator 28 in the stream of discharging air is employed for the purpose of regulating the rate of feed of the treating water. By thus regulating the rate at which the cold treating water is fed onto the sand, by means functionally responsive to the temperature of the stream of out-going air, I have found that apparatus constructed in accordance with my invention and capable of carrying out the process of my invention may be operated continuously and automatically and with little, if any actual personal attention of the operator or manual manipulation of the control valves.

It will be observed that in the apparatus which has been illustrated as one means for carrying out the principles of my invention, the cooling air flows through the treating zone in the same direction as the sand. This is highly desirable for the reason that by varying the velocity of such air stream proportionally amounts of undesirable finds contained in the sand may be removed from the cool dried sand as it is cascaded across the area confined by the shell 1 adjacent the discharge end thereof. When the direction of flow of the air is the same as the direction of flow of the sand there is, however, a practical lower limit to which the temperature of the sand being reconditioned may be reduced. If it should be desired to further reduce the temperature of the reconditioned sand, it is within the contemplation of my invention to carry the treating air through the treating zone in a direction counter to the direction of flow of the sand. This may be conveniently accomplished in the apparatus illustrated by merely moving the header 15 and its associated conduit 18, blower 19 etc. including the thermosensitive element 28 from the left end to the righthand end of the machine. The lefthand end of the shell 1 would then be open to the atmosphere to draw in cooled air at room temperature and the heated air would be withdrawn by means of a blower from the righthand end of the treater chamber. It is believed unnecessary to specifically illustrate this modification since from the foregoing description and disclosure, those skilled in the art should be able to provide the suggested change.

From the foregoing description it will be observed that I have provided an improved process and apparatus for the economical reconditioning of materials such as foundry sand and such apparatus and process is particularly advantageous for use in that it may be operated continuously

and in that it occupies only a relatively small floor space area as compared to the total amount of sand which it is capable of reconditioning in a given period of time.

5 Other modes of applying the principle of my invention may be employed instead of the one explained, change being made as regards the means and the steps herein disclosed, provided those stated by the following claim or its equivalent be employed.

10 I, therefore, particularly point out and distinctly claim as my invention:

In apparatus for reconditioning foundry sand,

the combination of a horizontally-inclined cylindrical shell provided on its inner periphery with lifting flights, means for rotating such shell, means for feeding a continuous stream of foundry sand to the feeding end of said shell, means for effecting a flow of air longitudinally through said shell, means for spraying water onto the sand in the feeding end of said shell, and means functionally responsive to variations in the temperature of the air stream discharged from said shell for varying the quantity of water thus sprayed onto the sand.

10 BENJAMIN A. SMITH.
